UNITED STATES PATENT OFFICE.

EDWARD FERGUSON CHANCE, OF SANDFORD ST. MARTIN, ENGLAND, ASSIGNOR TO CHANCE BROTHERS AND CO. LIMITED, OF GLASS WORKS, NEAR BIRMINGHAM, ENGLAND.

DESIGN FOR PLATE-GLASS.

43,187.

Specification for Design.

Patented Oct. 29, 1912.

Application filed July 25, 1910. Serial No. 573,815. Term of patent 14 years.

To all whom it may concern:

Be it known that I, EDWARD FERGUSON CHANCE, a subject of the King of Great Britain, residing at Sandford Park, Sandford St. Martin, Oxfordshire, England, have invented a new, original, and ornamental Design for Plate-Glass, of which the following is a specification, reference being had to the accompanying drawing, forming part thereof.

The figure is a plan view of a piece of plate glass showing my new design.

I claim:

The ornamental design for plate glass as shown.

In testimony whereof I have hereunto set my hand in presence of two subscribing witnesses.

EDWARD FERGUSON CHANCE.

Witnesses:

RICHARD SKERRETT,
